DOUBLE PACKAGING AND CUSHIONING STRIP

Ian A. Laird, Glasgow, Scotland, assignor to Vanant Products, Inc., Milwaukee, Wis., a corporation

Application December 31, 1952, Serial No. 328,947

2 Claims. (Cl. 206—62)

This invention appertains to a packaging and cushioning strip for the edge of a glass plate or pane of the type shown in the Martin Van Antwerpen Patent No. 2,603,349, issued July 15, 1952.

One of the primary objects of the present invention is to provide a cushioning strip which can be partially pre-formed by a paper converter and shipped in a flat condition, and thereafter folded and set up for application to the glass at its point of use.

Another salient object of the invention is to provide novel means for constructing a packaging and cushioning strip for the edges of glass plates or panes, so that the same can be set up for use without the employance of adhesives or fastening clips, etc.

A further object of this invention is the provision of a packaging and cushioning member formed from a single strip of material, embodying two or more V-shaped members having cushioning tongues struck out therefrom, with means for utilizing certain of the tongues as interlocking elements for holding the cushioning and packaging member in its assembled form, the construction being such that the interlocking tongues also perform the function of cushioning the glass.

With these and other objects in view, the invention consists in the novel construction, arrangement and formation of parts, as will be hereinafter more specifically described and claimed and illustrated in the accompanying drawing, in which drawing,

Figure 1 is a longitudinal sectional view through the improved packaging and cushioning strip in its set up condition, the section being taken on the line 1—1 of Figure 2, looking in the direction of the arrows;

Figure 2 is a plan view of the cushioning strip in its set up condition with parts thereof broken away and in section to illustrate structural detail;

Figure 3 is a transverse sectional view through the strip taken on the line 3—3 of Figure 2 looking in the direction of the arrows, and

Figure 4 is a plan view of the strip in its flat form for shipping to a consumer, and prior to being folded for use.

Referring to the drawing in detail, wherein similar reference characters designate corresponding parts throughout the several views, the letter S generally indicates the improved packaging and cushioning strip for one or more plates of glass G, shown in broken lines in Figure 1.

The strip S is formed from a single length of corrugated or like board, of a certain desired length and width, as best shown in Figure 4. This material is weakened along intermediate parallel lines 5 on opposite sides of the transverse center thereof and by parallel weakening lines 6, adjacent to the opposite ends thereof. Between the weakened lines 5 and 6 the strip is slotted by spaced parallel slits 7. The material between the slots 7 is slotted transversely, as at 8, at a point intermediate the ends of the parallel slots 7 to provide tongues 9 and 10. The strip is also weakened by score or like lines 11 on its under face. These score lines 11 extend transversely

2

of the strip and are arranged between the lines 5 and 6. This is also shown in Figure 4. The strip beyond the weakened lines 6 and adjacent to its opposite ends is provided with cutout tongues 12 and the striking out of these tongues 12 forms keeper openings 13 for the tongues 10 when the strip is set up for use, as will later appear.

The strip shown in Figure 4 is shipped to a consumer in its flat form and when the strip is to be used on the glass, the same is folded by the user in the following way.

The portions of the strip S beyond the weakened lines, now indicated by the reference character 14, are folded back on the lines 6 and V-shaped portions 15 are made by bending in the tongues 9 and 10 and folding the material or strip on the lines 11 and 5. The folded back portions 14 now provide an outer ply and the V-shaped portions 15 in effect, form an inner ply. The tongues 12 are bent outwardly to provide the keeper openings 13 and the tongues 10 are inserted in these keeper openings. The tongues 12 bear against the tongues 10 and provide a friction tension on the tongues 10. This holds the strip in its set up condition and the same can be applied to the glass plates by placing the strip on the edge of the plates with the plates in the slots in the V-portions 15, the slots being defined by the bending of the tongues 9 and 10. The tongues 9 and 10 and also the tongues 12 form a cushion for the edge of the glass plates. Lateral shifting of the plates in the V-portions 15 is prevented due to the engagement of the walls of the slots formed in the V-portions with the sides of the glass plates.

Obviously, with the two V-portions, the strip can be bent intermediate the V-portions around a corner.

From the foregoing description, it can be seen that I have provided an efficient and simple means for forming a cushioning and packaging strip. These strips can be placed around the glass at the desired points and the glass with the strips can be slipped into a shipping container (not shown).

Changes in details may be made without departing from the spirit or the scope of this invention, but what I claim as new is:

1. A packaging and cushioning member adapted to be placed about the edge of a sheet of glass comprising a longitudinally extending integral strip having inwardly projecting substantially V-shaped portions and folded back end cushion portions, said V-shaped portions being arranged in longitudinal alignment and being provided with longitudinally extending notches, said notches being also in longitudinal alignment for receiving the glass to be protected, the bent back end portions being provided with keeper openings, cushioning tongues struck out from the slots in the V-shaped portions, and certain of said tongues being received in the keeper openings, and tongues struck out from the keeper openings engaging the tongues inserted in said keeper openings.

2. A packaging and cushioning member comprising a longitudinally extending integral strip having an inwardly projecting substantially V-shaped portion and folded back end cushioned portions, each including a base having a keeper opening and cushioning tongues struck out from the sides of the V-shaped portion forming a slotted V-shaped portion, one of said cushioning tongues being received in one of said keeper openings.
